UNITED STATES PATENT OFFICE.

WILLIAM C. MARTINEAU AND CLARENCE R. MARTINEAU, OF ALBANY, NEW YORK.

CAR-SEAL.

1,115,952.

Specification of Letters Patent.

Patented Nov. 3, 1914.

Application filed June 9, 1914. Serial No. 843,971.

To all whom it may concern:

Be it known that we, WILLIAM C. MARTINEAU and CLARENCE R. MARTINEAU, both citizens of the United States, and residents 5 of Albany, Albany county, New York, have invented certain new and useful Improvements in Car-Seals, of which the following is a specification.

Our invention relates to seals for car, 10 store-room and like doors, meters, trunks and boxes in transportation, and similar purposes. The purpose of such a seal is of course not to prevent a forcible opening of the car or receptacle, but only to give 15 prompt notice that such opening has been made. It is therefore essential that the seal shall be incapable, after having been tampered with, of being restored to any appearance of its original integrity. 20 The object of our invention is to produce a cheap, simple seal in two parts only, having a tag portion capable of receiving the impress of a sealing tool, easily attachable by any unskilled person, and incapable of 25 restoration, as above stated.

In the drawings, Figure 1 is a front elevation of a seal embodying our invention in its engaged position; Fig. 2 shows in perspective the shackle detached; Fig. 3 is 30 a side elevation of the combined box and tag portion; Fig. 4 is a horizontal section through the plane 4—4, Fig. 1; Figs. 5 and 6 are respectively side and front elevations of a slightly modified form of box and tag 35 portion; Fig. 7 shows a modified shackle; Figs. 8 and 9 show modified parts ready for assembling, the shackle being partly broken away.

Referring to the first four figures, 11 designates an integral box and tag portion, 40 comprising tag 12, rear box wall 13, top box wall 14, front box wall 15, lower box wall 16 and plate 17, which last bears against and is firmly welded to rear wall 13. 21 is a shackle shown as formed from an integral strip of sheet metal and comprising body 22, having a quarter turn near each of its ends, and engaging portions, each having a sharp transverse return bend 23, 45 a series of longitudinal superposed return bends 24 and a hooked end consisting of members 25 and 26. The two parts are assembled by welding one end of the shackle within the box shown in Figs. 1 and 2, 50 plate 25 and the opposite face of bends 24

being secured to walls 13 and 15, the resilient hook member 26 being of course left free.

In practice, we prefer to weld within the box the left end of the shackle having a 60 slightly longer hook member 26, but this is of course immaterial.

In operation, the body 22 of the shackle is passed through the staple or through the two parts of a fixture to be secured together, 65 and the free end of the shackle pressed into the end of the box until the resilient hook members 26 have passed and engaged each other, as shown in Fig. 4. It will be seen that the ends of the box are completely filled by the bends 23 and 24, so as to absolutely 70 prevent the insertion of any tool by which the hooks might possibly be disengaged, and that the sharp transverse bends 23 are positioned half within and half without the ends of the box, so that any attempt to pull out the shackle end would result in breaking the strip at the already strained junction of the sides of the bend, thus leaving the box 75 effectually stoppered. This feature forms 80 no part of the present invention, being the subject of an application filed by Wm. C. Martineau, one of the present applicants, on March 13th, 1914, Serial Number 824,533.

The modification shown in Figs. 5 and 6 85 merely consists in forming the box portion of the integral box and tag 31 with its longer walls 34 and 36 at right angles with the tag 32, so that a shackle like that already described except for the commission of the 90 quarter turns would lie in the same plane with the tag, the shackle end being welded to these walls 34, 36. The alteration in the shackle is so slight that it is thought unnecessary to make a special drawing thereof. 95

In Fig. 7 is shown a shackle differing from that of Fig. 2 chiefly in that both ends of its loop or bight project from the same end of the box. Its body or loop 42 is bent at one end to form a transverse member 43 and a parallel member 44 having a reverted hook end 45, the member 44 and the portion of the strip opposite thereto, being as before firmly welded within the box, which may be as shown in either Fig. 1 or 5. The free 105 end of the shackle is formed into parts 23 to 36, as in Fig. 2. It will be understood that the operation of the complete device will be like that of the forms described.

In Figs. 8 and 9, the integral box and tag 110

portion 51 is composed of parts 52 to 57 precisely like the analogous parts 12 to 17 of Fig. 3, except that lower box wall 56 is very slightly shorter, so that plate 57 is spaced away from the rear wall 53 a distance equal to the thickness of the metal of which the shackle 61 is formed. This shackle, instead of being cut from a long strip of metal as before, is blanked from a sheet so as to have a lateral projection 62, shown as pierced at 63. This part 62 is substantially of equal dimensions with plate 57 and is welded between parts 53 and 57 of the box portion. It is first formed with engaging hooked ends constructed and functioning as already described. The end which is permanently within the box, comprising parts 64, 65 and 66, similar to parts 43, 44 and 45 of Fig. 7, is shown, the other end being broken away as being like the right ends of both forms of Figs. 2 and 7.

It will be obvious that modifications other than those shown may be made without departing from the spirit of our invention.

It may be well to explain that the tag portions 12, 32 and 52 are intended to be stamped both before and after assembling with insignia of ownership and the like; and that the thickness of the metal of which all parts are made is exaggerated for clearness of illustration. An advantageous gage for

both parts is about .015", though this may be varied as desired.

What we claim is:

1. A car seal comprising an integral box and tag portion consisting of a blank of thin sheet metal folded at one end to form a transverse open-end box, the long side of which is securely closed; and a shackle having a hook at each end and a thickened part adjacent each of said hooks and adapted to fill an end of said box, said hooks being adapted to interlock within said box, one end of said shackle being secured therein.

2. A car seal comprising an integral box and tag portion consisting of a blank of thin sheet metal folded at one end to form a transverse open-end box and a plate depending therefrom, said plate being welded to the body of the blank whereby the long side of said box is securely closed by a line of welding of substantial width; and a shackle having a hook at each end and a thickened part adjacent each of said hooks and adapted to fill an end of said box, said hooks being adapted to interlock within said box, one end of said shackle being welded therein.

WILLIAM C. MARTINEAU.
CLARENCE R. MARTINEAU.
